PUMP

Linus E. Russell, Springfield, Ohio

Application October 1, 1952, Serial No. 21,664

Term of patent 14 years

(Cl. D65—1)

To all whom it may concern:

Be it known, that I, Linus E. Russell, a citizen of the United States, residing at Springfield, Clark County, Ohio, has invented a new, original, and ornamental Design for a Pump, of which the following is a specification, reference being had to the accompanying drawing forming a part thereof, in which: Fig. 1 is a perspective view of a pump embodying my design;

Fig. 2 is a fragmentary perspective view of the bottom of the pump shown in Fig. 1.

The essential features of my design reside in the portions shown in full lines.

I claim:

The ornamental design for a pump, substantially as shown and described.

LINUS E. RUSSELL.
